US00D758219S

(12) **United States Design Patent**
Akana et al.

(10) **Patent No.:** **US D758,219 S**
(b4) **Date of Patent:** **** Jun. 7, 2016**

(54) **WEARABLE DEVICE**(71) Applicant: **Apple Inc.**, Cupertino, CA (US)

(72) Inventors: **Jody Akana**, San Francisco, CA (US); **Bartley K. Andre**, Palo Alto, CA (US); **Shota Aoyagi**, San Francisco, CA (US); **Anthony Michael Ashcroft**, San Francisco, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Marc A. Newson**, London (GB); **Matthew Dean Rohrbach**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Christopher J. Stringer**, Woodside, CA (US); **Eugene Antony Whang**, San Francisco, CA (US); **Rico Zörkendörfer**, San Francisco, CA (US)

(73) Assignee: **Apple Inc.**, Cupertino, CA (US)(**) Term: **14 Years**(21) Appl. No.: **29/519,401**(22) Filed: **Mar. 4, 2015****Related U.S. Application Data**

(63) Continuation of application No. 29/499,090, filed on Aug. 11, 2014, and a continuation of application No. 29/501,059, filed on Aug. 29, 2014, which is a continuation of application No. 29/499,090, filed on Aug. 11, 2014.

U.S. Appl. No. 29/498,987, filed Aug. 11, 2014.

(Continued)

Primary Examiner — Antoine D Davis(74) *Attorney, Agent, or Firm* — Sterne, Kessler, Goldstein & Fox P.L.L.C.**CLAIM**

The ornamental design for a wearable device, as shown and described.

DESCRIPTION

FIG. 1 is a bottom front perspective view of a wearable device showing our new design;

FIG. 2 is a top rear perspective view thereof;

FIG. 3 is a bottom view thereof;

FIG. 4 is a top view thereof;

FIG. 5 is a front view thereof;

FIG. 6 is a rear view thereof;

FIG. 7 is a right side view thereof; and,

FIG. 8 is a left side view thereof.

The broken lines in the figures show portions of the wearable device that form no part of the claimed design.

1 Claim, 4 Drawing Sheets(56)
